UNITED STATES PATENT OFFICE.

HENRY AIKEN, OF PITTSBURG, PENNSYLVANIA.

BLOWING-ENGINE.

No. 872,603.

Specification of Letters Patent.

Patented Dec. 3, 1907.

Application filed July 25, 1904. Serial No. 217,904.

To all whom it may concern:

Be it known that I, HENRY AIKEN, of Pittsburgh, Allegheny county, Pennsylvania, have invented a new and useful Improvement 5 in Blowing-Engines, of which the following is a full, clear, and exact description, reference being had to the accompanying drawings, forming part of this specification, in which—

10 Figure 1 is an elevation of a blowing engine constructed in accordance with my invention; Fig. 2 is a vertical section of the upper portion of the engine; Fig. 3 is a vertical section of the lower portion, these two figures being 15 continuations of each other, and intended to be read together; Fig. 4 is a horizontal section on the line IV—IV of Fig. 2; Fig. 5 is a top plan view of the upper head; Fig. 6 is a vertical section of the blowing engine on a 20 smaller scale, the plane of section being the same as in Figs. 2 and 3; and Fig. 7 is a similar view on a plane at right angles to Fig. 6.

My invention is an improvement upon the blowing engine for which on December 1, 25 1903, I filed an application for Letters Patent, Serial No. 183,354, and its purpose is to provide a double-acting blowing engine which will compress the air and discharge it to the blast-main both on the up-stroke and down- 30 stroke of the piston. In the apparatus shown in the application above referred to, the air was compressed and discharged into the blast main on the down-stroke only.

In the drawing, 2 represents a vertical explosion-cylinder having a water-jacket 3, a lower water-cooled head 4, valves 5, 5' which admit air and gas respectively into the explosion cylinder, and valves 6 for the exhaust of the spent gases, or the valve-mechanism may 40 be arranged so as to admit previously mixed gas and air to the cylinder. Above the explosion-cylinder 2, and in vertical line therewith, is a second explosion-cylinder 7 which is also water-cooled and is of larger diameter 45 than the cylinder 2, thus affording at its lower end an annular head 8 in which are valves 9, 10 for admission of gas and air and the discharge of the spent gases. Above the explosion-cylinder 7 and in vertical line therewith is the air-compressing cylinder 11 which is of greater diameter than the cylinder 7 and has at the annular head afforded at its lower end air-inlet valves 12 and air-outlet valves 13, the latter leading to a blast-main 14.

The upper end of the compression-cylinder 55 11 has also air-inlet valves 12' and air-outlet valves 13'.

The pistons of the cylinders 2, 7 and 11 are preferably made as an integral structure. The compound piston has a portion of smallest diameter 15 which works in the cylinder 2 and moves upwardly into the cylinder 7, a portion 16 of intermediate diameter which works in the cylinder 7 and moves upwardly into the cylinder 11, and a portion 17 of the greatest diameter which is the piston for the air-compressing cylinder 11. These pistons are weighted with a central weight 18 which is set within the compound piston in such manner as to leave an intermediate space 19. 60 70 for circulation of water or other cooling medium introduced through a central passage 20 from a telescoping pipe 21 and discharged through a telescoping outlet pipe 22.

The cylinders 2 and 7 have igniters 23 and 75 24 operated preferably by suitable cams and connecting rods 25 from one of the driven parts of the engine.

The engine has fly-wheels 26 mounted on a main shaft 27, whose cranks are connected 80 by pitmen 28 to cross-heads 29 which move in cross-head guides 30. The cross-heads are connected with the piston 17 by vertical rods 31 which extend through stuffing boxes 31' at the base of the cylinder 11. The pistons are therefore connected with the fly-wheel shaft without passing rods through the explosion-cylinders and without the necessity of providing these cylinders with stuffing boxes, which on account of the heat 85 90 generated by the frequent explosions would be especially difficult to maintain. By making the connection from the piston in this manner I avoid the ordinary walking beam connection extending outwardly from the center of the engine to the connecting rods which has been a source of great difficulty in engines heretofore employed. In my engine the connection between the piston and the crank-shaft is in straight lines, and 95 100 I thus secure a simple and strong device free from the difficulties above mentioned.

The valve-mechanism by which the explosive charge of gas and air is admitted to the cylinders 2 and 7, and by which the exhaust of the spent gases from the cylinders is effected, is controlled by rods 32 and levers 105 33 or other suitable mechanism operated by

cams 34 on shafts which derive their power through gearing 35 from the main crank-shaft.

Figs. 2 and 3 show the parts of the engine 5 as they are when the compound piston has been lifted to its full extent by an explosion which has taken place say in the lower explosion-cylinder 2. After the out-stroke has been effected by such explosion, the piston 10 makes its return stroke by gravity, the fly-wheel being employed for the purpose of imparting exactness of length to the stroke and securing greater regularity of motion in displacing the compressed air from the com- 15 pression-cylinder 11. On the return of the piston which is thus effected by gravity, air is compressed in the lower part of the cylinder 11 and is displaced through the valves 13 to the blast-main, while air is drawn into 20 the upper portion of the cylinder 11 through the inlet-valves 12'. On this same down-stroke the explosive charge of air and gas which has been drawn into the cylinder 7 on the up-stroke is compressed in that cylinder, 25 and the spent gases from the previous explosion in the cylinder 2 are displaced through the exhaust-valves 6. When the piston has reached the end of its down or return stroke, the compressed gases in the 30 cylinder 7 are ignited, the exact moment of the ignition being determined by setting the cams of the igniting mechanism at the point desired. The resulting explosion impels the compound piston in its up-stroke, the end 35 of which is illustrated in Fig. 2. In this up-ward motion, an explosive charge of air and gas is drawn into the bottom cylinder 2, and air is compressed in the upper end of the cylinder 11 and is discharged into the blast- 40 main through the valves 13'. When the compound piston returns by gravity, air is compressed in the lower portion of the cylinder 11 and is discharged through the valves 13 as above explained; the spent gases are 45 exhausted from the exhaust-valves at the base of the cylinder 7; and the explosive charge contained in the lowest cylinder 2 is compressed preliminarily to the next ignition which takes place when the piston reaches 50 the end of its down-stroke. It will thus be seen that compression and discharge of air into the blast-main is effected at each up-stroke and each down-stroke of the piston 18; that an explosion occurs and an impulse 55 is imparted to the piston at the end of each down-stroke, the explosions taking place alternately in the two explosion-cylinders; and that the return of the piston is effected by gravity and serves not only to compress the 60 air in the cylinder 11, but also to expel the spent gases from the cylinder in which the explosion last occurred and to compress the explosive charge of gas and air in the other cylinder.

65 Some of the advantages of this construc-

tion are that by using an explosion of gas to move the piston vertically upward and the weight of the piston to return it to its lower portion and to compress the air in the intermediate annular cylinder, and compressing 70 the air on the down-stroke as well as the up-stroke, I get all the advantages of an engine operated by an explosion in both directions. The lower cylinder 2 and the annular cylinder 7 are preferably of approximate equal 75 areas, so that the explosion in one cylinder is equivalent in its effect to the explosion in the other.

Within the scope of my invention as defined in the claims the parts may be modified 80 in many ways, since

What I claim is:

1. An engine comprising an upright explosive cylinder having at least two sections of different diameter, and a piston having 85 portions fitting the respective cylinder sections, the return stroke of the piston being effected by gravity, substantially as described.

2. An engine comprising an explosive cyl- 90 inder having at least two sections of different diameter, a piston having portions fitting the respective cylinder sections, and valves in the inner head of the larger cylinder sections, substantially as described. 95

3. An engine comprising an explosive cyl- 100 inder having at least two sections of different diameters, a piston having portions fitting the respective cylinder sections, the working area of the piston portions being substan- 100 tially equal, and valves in the inner head of the larger cylinder section, substantially as described.

4. An engine having two explosion cylinders in endwise vertical alinement, an air 105 compression cylinder in alinement with the explosion cylinders and a compound piston arranged to effect its return stroke by gravity and to compress air in the compression cylinder on both strokes; substantially as 110 described.

5. An engine having two explosion-cylinders in endwise alinement and directly connected with each other, an air compression cylinder also in endwise alinement, a com- 115 pound piston having portions fitting in the several cylinders, and valves located in the annular heads between the cylinders; sub- stantially as described.

6. An engine having an explosion cylin- 120 der, a compression cylinder directly connected to the explosion cylinder, a com- pound vertically movable piston in said cylinders, said piston being weighted to effect its return stroke by gravity and an 125 air discharge and air-inlet valves both above and below the compression piston; substan- tially as described.

7. An engine having a vertically movable piston adapted to effect its return stroke by 130

- gravity, a compression-cylinder and piston connected therewith, and air-discharge and air-inlet valves above and below the compression-piston, there being two explosion-cylinders adapted to operate at alternate out-strokes of the piston, substantially as described.
8. A compression-cylinder, and two explosion cylinders, means for effecting alternate explosions in the explosion-cylinders to cause the out-stroke of the pistons, means for causing the return-stroke by gravity and in such return-stroke compressing a charge in one explosion-cylinder and exhausting the gases from the other explosion-cylinder, and valves for discharging the compressed air from the compression-cylinder at each in-stroke and out-stroke of the piston; substantially as described.
10. An engine comprising an upright cylinder having three sections of progressively increasing diameter, a piston having portions fitting the respective cylinder sections, and means for effecting explosions in two of the cylinder sections for rendering them successively active to lift the piston, the return stroke of the piston being effected by gravity, and the third cylinder section constituting a compressor cylinder, substantially as described.
15. An engine having two explosion cylinders and a compression cylinder, said cylinders being directly connected and in endwise vertical alinement with each other, a com-
- 5 pound piston working in said cylinders and arranged to effect its return stroke by gravity, and air-inlet and air-discharge valves above and below the piston on the compression cylinder; substantially as described.
11. An engine comprising a compressor cylinder and at least two explosive cylinders in vertical alinement, pistons working in the cylinders and connected for simultaneous movement, and means for effecting explosions in the explosive cylinders to render the same successively active to lift the pistons, the return stroke being effected by gravity, substantially as described.
12. In a blowing engine, an upright cylinder having three sections of progressively increasing diameter, a piston having portions fitting the respective cylinder sections and weighted to effect its return stroke by gravity, the two smaller cylinder sections being explosive cylinders and the larger section being a compressor cylinder, each head of the compressor cylinder having inlet and outlet valves, and admission and exhaust valves in the head of the middle cylinder section around the smaller section, substantially as described.
15. In testimony whereof I have hereunto set my hand.

HENRY AIKEN.
